CARDBOARD BOX

Walter W. Deline, Denver, Colo.

Application September 20, 1938, Serial No. 230,767

8 Claims. (Cl. 229—23)

This invention relates to knock-down cardboard boxes, more particularly for use for packing candy.

The principal object of this invention is to provide a box of this character which can be packed and shipped to the user in a flat, knocked-down condition and which can be quickly and easily erected by the salesmen or packers at the time of packing the box.

Other objects of the invention are, to provide a box which can be quickly and easily assembled and which when assembled will rigidly and securely maintain all of its parts in position without the use of glue, staples, cement, or other fastening devices; and to provide a box in which the lid will be hinged to the box so that it may be lifted to expose the contents and which when closed will be firmly held in place.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a plan view of the bottom member of the improved box.

Fig. 2 is a plan view of the lid thereof.

Fig. 3 illustrates the side band of the box.

Fig. 4 is a perspective view of the complete assembled box.

Fig. 5 is a detail section along the box edge illustrating the relation between the top, bottom and side thereof.

While not limited to the exact shape or design shown, the new construction is particularly applicable to a heart-shaped box as illustrated. The complete box consists of three pieces, a bottom 10, a lid 11, and a side band 12.

The bottom is formed with a peripheral series of elongated slots 13 and with a terminal V-shaped slot 14.

The top is provided with a series of similar slots 15 and 15' positioned intermediate the positions of the slots 13 in the bottom. The slots 15' are placed in alignment with each other.

The side band is formed along its bottom edge with a series of hooked tongues 16, the hooks of adjacent tongues facing in opposite directions, and with a terminal hooked tongue 16 at each

extremity of the band. The upper edge of the band 12 is provided with a series of rectangular top tongues 17 and similar end tongues 19, the latter being placed near the extremities of the band. The band is creased intermediate its extremities as shown at 18 to provide a middle fold point.

In assembling the box one terminal tongue 16 is hooked into the V-shaped slot 14, the band is then distorted to allow the next hooked shaped 10 tongue 16 to be placed in the next elongated perforation 13, the band is now allowed to resume its normal curve around the periphery of the bottom which acts to lock the hook of the next tongue 15 into its place.

This procedure is continued completely around the bottom, each time before inserting the band it is straightened to increase its length, the tongues are then inserted and the band is allowed to curve to pull the tongues to the locked position. At 20 the point of a heart box the band is folded along the fold line 18 and returned along the opposite edge of the bottom until its final terminal tongue 16 is locked in the terminal slot 14.

When once assembled, it is almost impossible 25 to remove the band 12 without destroying the box. This is due to the fact that the final curved shape of the band acts to pull the locking tongues under the end edges of the slots to prevent them from unhooking.

After the box is packed, the lid 11 is placed over the top tongues 17 and 19, the latter entering the slots 15', and pushed downwardly on the box. These tongues are naturally curved due to the curve of the side and the slots are straight. 35 This curving action of the tongues acts to lock the lid in place so that it requires considerable pull to remove it from the tongues.

If the lid be lifted at the pointed extremity, it will pull from the side tongues 17 and hinge on 40 the two aligned end tongues 19 so that the lid may be lifted without completely removing it and when released will snap back upon the box due to the inherent elasticity of the two tongues 19.

The invention is particularly applicable to boxes, the outline of which is curved for in a straight box it would be difficult to insert two oppositely facing, hooked tongues without destroying the hooks thereof. In curved outline boxes, however, the side may be straightened to allow the tongues to pass through the slots and then released to curve and pull the tongues into the locking position.

While a specific form of the improvement has 55

been described and illustrated herein, it is desired to be understood that the same may be varied, within the scope of the appended claims, without departing from the spirit of the invention.

5. Having thus described the invention what is claimed and desired secured by Letters Patent is:

1. An erectable box construction comprising: a bottom member; a lid, said bottom member and said lid being provided with straight, elongated 10 slots along their peripheral edges; and a side band of a width equal to the height of said box, said side band having tongues along its edges for engaging in the slots of said top and bottom member the tongues along the bottom edge having hooked ends, the outline of said box being curved so that said side band may be straightened to increase the distance in a straight line between adjacent tongues to allow said hooked ends to be inserted in said slots, the hooks of said 20 tongues being faced in opposite directions in pairs.

2. An erectable box construction comprising: a bottom member; a lid, said bottom member and said lid being provided with straight, elongated 25 slots along their peripheral edges; and a side band of a width equal to the height of said box, said side band having tongues along its edges for engaging in the slots of said top and bottom member the tongues along the bottom edge having hooked ends, the outline of said box being curved so that said tongues will be bent upon an arc, said slots being straight so that the tongues must be distorted to pass through the slots, the 30 distorting action thereof acting to lock the 35 tongues in the slots.

3. A knock-down, heart-shaped box comprising: a heart-shaped bottom member; a series of straight, elongated slots around said bottom member adjacent the edge thereof; a V-shaped 40 terminal slot at the notch of the heart-shape; a flexible side band; a series of tongues projecting downward from said band corresponding in number to said elongated slots; and a terminal tongue 45 projecting downward from each extremity of said band, the spacing between said tongues being greater than the spacing between said elongated slots; hooks formed on each of said tongues, the hooks of adjacent tongues being directed in opposite directions, the hooks of the terminal tongues 50 being directed away from the extremities, both said terminal tongues being engaged in said V-shaped terminal slot and the remaining tongues being engaged in the elongated straight slots.

4. A knock-down, heart-shaped box comprising: a heart-shaped bottom member; a series of straight, elongated slots around said bottom member adjacent the edge thereof; a V-shaped 55 terminal slot at the notch of the heart-shape; a flexible side band; a series of hooked tongues projecting downward from said band corresponding in number to said elongated slots; a terminal tongue 60 projecting downward from each extremity of said band, the spacing between said tongues being greater than the spacing between said elongated slots; hooks formed on each of said tongues, the hooks of adjacent tongues being directed in opposite directions, the hooks of the terminal tongues being directed away from the 65 extremities, both said terminal tongues being engaged in said V-shaped terminal slot and the re-

maining tongues being engaged in the elongated straight slots; a second series of tongues projecting from the top edge of said band; and a lid member corresponding in outline to said bottom member, said lid member being provided with 5 perforations for receiving said second series of tongues.

5. A knock-down, heart-shaped box comprising: a heart-shaped bottom member; a series of straight, elongated slots around said bottom 10 member adjacent the edge thereof; a V-shaped terminal slot at the notch of the heart-shape; a flexible side band; a series of hooked tongues projecting downward from said band corresponding in number to said elongated slots; a terminal 15 tongue projecting downward from each extremity of said band, the spacing between said tongues being greater than the spacing between said elongated slots; hooks formed on each of said tongues, the hooks of adjacent tongues being directed in 20 opposite directions, the hooks of the terminal tongues being directed away from the extremities, both said terminal tongues being engaged in the elongated 25 straight slots; a second series of tongues projecting from the top edge of said band; and a lid member corresponding in outline to said bottom member, said lid member being provided with 30 perforations for receiving said second series of tongues, two of the tongues of said second series being in alignment with each other to act as a hinge.

6. An erectable, heart-shaped box comprising: a heart-shaped lid; a single continuous side band 35 curved to conform to shape of said bottom and lid; a series of elongated tongues projecting from the upper and lower edges of said side band through elongated, straight-sided slots in said bottom and in said lid, said tongues being held 40 in place by the tendency of the tongues to resume the normal curvature of said band within said straight-sided slots.

7. An erectable, heart-shaped box comprising: a heart-shaped bottom; a heart-shaped lid; a 45 single continuous side band curved to conform to shape of said bottom and lid; a series of elongated tongues projecting from the upper and lower edges of said side band through elongated, straight-sided slots in said bottom and in said 50 lid; a projecting hook formed on one side of each of the tongues on the lower edge of said band, each of said hooks being pulled into engagement with the extremity of one of said slots by the shortening of the distance in a straight line between adjacent tongues due to the tendency of 55 the band to curve to conform to the shape of said bottom.

8. An erectable, heart-shaped box comprising: a heart-shaped bottom; a heart-shaped lid; a 60 single continuous side band curved to conform to shape of said bottom and lid; a series of elongated tongues projecting from the upper and lower edges of said side band through elongated, straight-sided slots in said bottom and in said lid, 65 said tongues being held in place by the tendency of the tongues to resume the normal curvature of said band within said straight-sided slots.
